A. SEYDEL

AERIAL VEHICLE

Filed Aug. 23, 1922

INVENTOR

A. SEYDEL

BY

M. E. Elam
ATTORNEY

UNITED STATES PATENT OFFICE.

ADOLF SEYDEL, OF BROOKLYN, NEW YORK.

AERIAL VEHICLE.

Application filed August 23, 1922. Serial No. 583,717.

To all whom it may concern:

Be it known that I, ADOLF SEYDEL, a citizen of Germany, residing at Brooklyn, New York, in the county of Kings and State of New York, have invented certain new and useful Improvements in Aerial Vehicles, of which the following is a specification.

This invention relates to devices by which aerial navigation may be attained by manual effort and has as its object to provide an apparatus simulating a bird having a buoyant body, movable wings and dirigible tail or rudder.

A further purpose is in the provision of a chamber in the vehicle for the operator and means whereby the wings may be actuated by the rider.

These objects are attained by the novel design, construction and arrangement of parts hereafter described and shown in the accompanying drawing, in which:—

Figure 1 is a plan view of an embodiment of the invention.

Figure 2 is a side elevational view of the same.

Figure 3 is a transverse sectional view taken on line 3—3 of Figure 1.

In the drawing, the numeral 10 designates the forward portion of the body having at its front a raised head 11 and connected to the rear body portion 12 by a central portion 13.

In plan, the structure is boat shaped, sharp at the front and rounded at the rear.

35 In the center portion 13 is a vertical well or cockpit 14 having a partition 15 containing a pair of openings 16 through which the legs of the rider may be extended when seated on the floor 15.

40 The entire body is hollow being merely a thin casing enclosing an inner space connected from front to rear by the side passages 17 at the cockpit which, as shown, is cylindrical, as is also the cross section of the casing.

45 The space within the casing is gas and water tight and adapted to contain any

lighter-than-air gas by which the body is rendered so buoyant as nearly or quite nearly to float in the air when equipped and carrying a rider.

Attached by hinges 18 to the upper part of the body, on each side thereof, are wings 19, generally concavo-convex and having an area suited for their purpose.

These wings are manipulated by the arms of the rider which pass through pairs of loops 20 secured to the underside of the wings in such position as to be readily operable by a person sitting in the cock-pit 14.

A rigid horizontal tail 21 is attached to the rear end of the body and engaged by hinges 22, to its outer edge, is horizontal rudder 23 by which the body may be inclined from a level plane in either direction when moving.

A vertical rudder 24 is engaged by hinge connections 25 to the end of the body below the tail 21 for steering the vehicle sidewise, suitable connections, not shown, extending from the rudders to the cock-pit to be operated by the rider.

Due to the buoyancy of the vehicle it may be readily navigated in the air with reasonable exertion on the part of the rider and obviously steered as desired.

Having thus described my invention, the manner of its construction and operation, what I claim as new and desire to secure by Letters Patents, is:—

An aerial vehicle comprising a hollow body raised at the front and of substantially circular cross section thruout, said body tapering from the center fore and aft, a vertical cock-pit in the center of said body, said cock-pit having a flooring through which the legs of the rider extend, a pair of wings hinged to said body, hooks on the underside of said wings to engage the arms of the rider, a tail on said body, and rudders for changing the inclination and direction of the vehicle.

In witness whereof I affix my signature.

ADOLF SEYDEL.
